CLAIM

The ornamental design for a butter dish and cover assembly, as shown and described.

DESCRIPTION

FIG. 1 is a front, top, right perspective view of a butter dish and cover assembly, showing the claimed design;

FIG. 2 is an exploded perspective view of the butter dish and cover assembly;

FIG. 3 is a front, top, right perspective view of the cover;

FIG. 4 is a front elevation view of the cover;

FIG. 5 is a rear elevation view of the cover;

FIG. 6 is a left side elevation view of the cover;

FIG. 7 is a right side elevation view of the cover;

FIG. 8 is a top plan view of the cover;

FIG. 9 is a bottom plan view of the cover;

FIG. 10 is a front, top, right perspective view of the butter dish;

FIG. 11 is a front elevation view of the butter dish;

FIG. 12 is a rear elevation view of the butter dish;

FIG. 13 is a left side elevation view of the butter dish;

FIG. 14 is a right side elevation view of the butter dish;

FIG. 15 is a top plan view of the butter dish;

FIG. 16 is a bottom plan view of the butter dish; and,

FIG. 17 is a cross-sectional view taken along line 17-17 in FIG. 2.
